United States Patent

Des. 241,851
Patented Oct. 12, 1976

241,851

DYNAMOELECTRIC MACHINE

Robert G. Bartheld and Paul Diamant, Cincinnati, Ohio,
assignors to Allis-Chalmers Corporation, Milwaukee,
Wis.

Filed Mar. 7, 1975, Ser. No. 556,399

Term of patent 14 years

Int. Cl. D13—01

U.S. Cl. D26—5 A

Fig. 1

FIG. 1 is a perspective view taken from the front, top and one side of a dynamoelectric machine showing our new design; and

FIG. 2 is a perspective view taken from the rear, top and side opposite that shown in FIG. 1.

We claim:

The ornamental design for a dynamoelectric machine, as shown.
